D. FORBES

ADJUSTABLE HOLDER

Filed April 22, 1927

40 41 Inventor:
Dorothy Forbes,
by Wright Broom Quincy / Mary
Atlys.

Patented Nov. 20, 1928.

UNITED STATES PATENT OFFICE.

DOROTHY FORBES, OF BOSTON, MASSACHUSETTS.

ADJUSTABLE HOLDER.

Application filed April 22, 1927. Serial No. 185,762.

The object of this invention is to provide a simple and readily adjustable holder including a rack adapted to confine an article such as an opened book, and means for supporting the rack in various positions, permitting convenient inspection of the confined article, the chief object being to permit a person lying in bed to conveniently read a book confined by the rack, the latter being universally adjustable to any position that the reader may desire.

Of the accompanying drawings forming a part of this specification,—

Figure 1 is a side view of a portion of a bed equipped with a holder embodying the invention.

Figure 2 is a top plan view of the same.

Figure 3 is a fragmentary perspective view, showing portions of the holder.

Figure 4 is a section on line 4—4 of Figure 1.

Figure 5 is a front view of the rack.

Figure 6 is a section on line 6—6 of Figure 5.

Figure 7 is a section on line 7—7 of Figure 6.

Figure 8 is a section on line 8—8 of Figure 5.

The same reference characters indicate the same parts in all of the figures.

In the drawings 12 designates a clamp, having means as clearly shown by Figure 4, for engaging an upright post 13 of a bedstead at a point above the bedding, the post being an element of the head portion of the bedstead. The clamp is provided with a vertical socket 14, which is vertical when the clamp is attached to the post. 15 and 18 designate members of a crane, the member 18 being rigidly connected with the member 15 by an elbow 17. The member 15 is vertical and is adapted to turn and move endwise in the clamp socket 14. The member 18 is horizontal and arranged to overhang the bed, as shown by Figures 1 and 2. Connected by a

T 19 with the outer end of the crane member 18 is a terminal arm 20, having a trunnion 21 (Figure 3) journaled in the T 19, the arm 20 being connected by an elbow 22 with the trunnion and extending downwardly therefrom toward the bed. The T and the trunnion constitute a hinge connection between the terminal arm 20 and the crane member 18, permitting the arm 20 to swing in a vertical plane.

The lower end of the terminal arm 20 is pro-

vided with a socket member of a universal or ball and socket joint. Said member includes an elbow 23 (Figure 6), fixed to the lower end of the arm 20 and provided with a recess 24 and with a cupped jaw 25, and a movable cupped jaw 26, having a shank 27, movable in the recess 24, and adjustable by a clamping screw 28.

29 designates a rack which has flat outer and inner sides, and is provided with means hereinafter described for releasably confining an article such as a book 30, against its outer side, and with a ball member of a universal joint at its rear side, said member being a spherical enlargement 31 of a shank 32, fixed to the central portion of the rack and projecting from the rear side thereof. The ball member is interengaged with the socket member to permit a universal swinging adjustment of the rack, so that it may face downwardly toward the bed, as shown by Figure 1, and may face in various other directions. The socket member is compressible by movement of the jaw 26 toward the jaw 25 caused by the screw 28, to lock the universal joint and maintain the rack in any position to which it may be swung.

The rack may be bodily adjusted vertically by an endwise movement of the crane member 15, in the clamp socket 14, to vary the height of the rack above the bed, and horizontally by a partial rotation of the member 15 in the socket, to move the rack toward and from a longitudinal edge of the bed. A vertical adjustment of the crane and rack may be maintained by a stop collar 34, bearing on the clamp socket 14, and adjustably secured to the member section 15 by a set screw 35. The rack may be bodily adjusted by swinging the terminal arm 20 on the hinge joint connecting it with the crane member 18, a set screw 36 being engaged with the T 19 to lock the trunnion 21 in the T. This swinging adjustment moves the rack toward and from the head of the bed.

I will now describe the preferred means for releasably securing a book to the outer side of the rack 29.

38 designates a ledge fixed to the lower edge of the rack at the outer side thereof, the ledge having a groove 39 in its upper side, receiving the lower ends of the cover and back of the book 30 when the book is opened, the lower ends of the leaves of the book being above the grooves, so that they may be turned.

40 designates a bar which is slidable on the collar 34 and set screw 35 maintaining the rack toward and from the ledge 38, and is located above the book and at any distance from the upper end thereof required by the 5 length of the book. The bar 40 is provided at its opposite ends with angular ears, each including a portion 41 (Figures 5 and 8), extending across an end of the rack, and a portion 42 bearing on the rear side of the 10 rack. The bar is maintained by friction in any position to which it may be adjusted on the rack. To this end, resilient friction shoes 43, are interposed between the neck portions 41 and the ends of the rack, and are caused 15 to bear more or less forcibly on said ends, by adjusting screws 44 engaged with tapped sockets in the neck portions 41.

Resilient clips 45, preferably of wire, are connected with the ledge 38, and project upwardly therefrom to bear on the exposed leaves of the opened book, each clip preferably including a shank portion 46, inserted in a socket 47 in the ledge, and a coiled portion 48, connecting the shank portion with 25 the body of the clip. The shank portion is adapted to turn in its socket, so that the clips may be displaced, as indicated by dotted lines in Figure 5, to permit the turning of the leaves. There may be a plurality of 30 sockets 47, as shown by Figure 5, in either of which a clip shank may be inserted, so that the clips may be conformed to relatively wide and relatively narrow books.

Similar clips 45^a are similarly connected 35 with the bar 40 and project downwardly therefrom. The bar may be provided with supplemental clips 49, pivoted at 50 to the bar and located between the clips 45^a, the clips 49 being likewise displaceable.

40 The rack is horizontally adjustable relative to the bed by swinging movements of the crane, and angularly adjustable relative to the terminal arm by movements of one of the universal joint members relative to the 45 other, so that the rack may be supported at various angles permitting the occupant of the bed to face either upwardly or sidewise when reading.

The vertical adjustability of the crane 50 member 15 in the socket 14 enables the height of the rack above the bed to be varied, the

collar 34 and set screw 35 maintaining the desired vertical adjustment. The hinge connection between the terminal arm 20 and the crane member 18 shown by Figures 2 and 3 5 permits said arm and the rack to swing in a vertical plane toward and from the head of the bedstead, and thus adjust the rack at any desired distance from the eyes of a recumbent reader, the adjustment being maintained 60 by locking the hinge connection by tightening the set screw 36, and thus preventing swinging movements of the arm.

I claim:

For use with a bedstead and a bed thereon, 65 an adjustable holder comprising, in combination, a clamp adapted to engage opposite sides of one of the upright corner posts of the bedstead, above the bed, and provided with a socket offset from the clamp and post; 70 a crane including an upright member journaled in the socket and vertically adjustable therein, and provided with means whereby it may be supported by the socket and permitted to turn therein when in any position 75 to which it is vertically adjustable, the crane including also a horizontal member fixed to and projecting from the upper end of the upright member, and adapted to swing horizontally on the axis provided by the upright 80 member and the socket to different angular positions relative to the corner post and the bed; a terminal arm hinged to the swinging end of the horizontal member and adjustable to a vertical and to various inclined positions, 85 means being provided for securing said arm to the crane to hold the arm in any position to which it may be adjusted; a supporting rack; and a ball and socket joint connecting 90 said rack with the lower end of the terminal 95 arm, said joint being provided with means whereby it may be locked to confine the rack in different angular positions relative to the terminal arm, the arrangement being such that the rack may be supported in various positions over the bed, and may be displaced with the terminal arm and the crane to leave the bed unobstructed.

In testimony whereof I have affixed my signature.

DOROTHY FORBES.
